(57) **CLAIM**

The ornamental design for a needle counter, as shown and described.

DESCRIPTION

FIG. 1 is a top and side perspective view of a needle counter showing a new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a back view thereof.

The dashed lines of FIGS. 1, 2 and 3 show environmental conditions only and form no part of the claimed design.
